UNITED STATES PATENT OFFICE.

WILLIAM C. WARREN AND ARTHUR SMITHSON, OF SEDAN, MINNESOTA.

WAGON-BOX SUPPORT.

SPECIFICATION forming part of Letters Patent No. 658,904, dated October 2, 1900.

Application filed April 19, 1899. Renewed March 23, 1900. Serial No. 9,965. (No model.)

To all whom it may concern:

Be it known that we, WILLIAM C. WARREN and ARTHUR SMITHSON, citizens of the United States, residing at Sedan, in the county of Pope and State of Minnesota, have invented 5 certain new and useful Improvements in Wagon-Box Supports; and we do declare the following to be a full, clear, and exact description of the invention, such as will enable 10 others skilled in the art to which it appertains to make and use the same, reference being had to the accompanying drawings, and to the letters of reference marked thereon, which form a part of this specification. 15 Our invention relates to improvements in wagon-box supports; and the object of our invention is to provide a novel cheaply-manufactured wagon-box support which will strengthen the box and at the same time se- 20 cure it loosely in its place upon the bolster and protect it from undue wear against the bolster and the stakes. This manifold object we attain by the novel construction and ar- 25 arrangement illustrated in the accompanying drawings, in which—

Figure 1 is a rear end view of a wagon-box and bolster with our device applied to same. Fig. 2 is a sectional side view on the line *a a* in Fig. 1. Fig. 3 is a bottom view of the box- 30 support alone detached from the wagon-box. Referring to the drawings by letters of reference, A is the box, B the bolster, and C the stakes, of an ordinary box-wagon—like “farmers’ wagons,” for instance. In this 35 class of wagons the box is usually provided at its bottom with two wooden cleats fitting at both sides of the bolster, and the stakes C are left to rub freely against the sides of the wagon-box, which is thereby often worn out 40 or badly damaged, especially as the wooden cleats by wear and shrinkage soon allow the box to play considerably on the bolster. To overcome these defects, we provide the sheet metallic lining or plate D, which we form with 45 two deep grooves or corrugations E and the flanges F, which stand in plane with the body of the plate and are provided with holes G for securing the plate by rivets or screws H across the bottom of the wagon-box,

so that the corrugations E pass snugly down 50 at both sides of the bolster B and take the place of the old-style cleats, but in a more effective manner both for guiding, strength- 55 ening, and protecting the box.

The ends of the plate D are formed with 55 broad hooks J, extending upward at each side of the box, to which they are secured by the rivets, bolts, or screws K. These hooks may preferably be let into the sides of the box, as shown in Fig. 1, about flush with the wood. 60 Their service is to strengthen and protect the box and protect it against wear by the adja- 65 cent stakes C. By lining the stakes and the bolster with sheet-iron (not shown) it is ob- 70 vious that our invention becomes still more serviceable and valuable in that it reduces wear and tear of the parts in question to a minimum.

Having thus described our invention, what we claim as new, and desire to secure by Let- 70 ters Patent, is—

1. The combination with a wagon-box and the bolster supporting it, of a metallic sheet interposed between the bolster and the wagon- 75 box, and adapted to be secured to the latter; 75 said sheet having solid end portions as wide as the bolster extending upward at both sides of the wagon-box, it also having two corrugations depending downward one in the front and the other in the rear of the bolster, 80 substantially as and for the purposes set forth.

2. The combination with the box, bolster and bolster-stakes of a wagon, of a sheet metallic lining extending all along the top of the bolster and up between the bolster stakes 85 or standards and the box, said lining being securable to the wagon-box, and having two corrugations depending one in front and the other in the rear of the bolster, substantially 90 as and for the purposes set forth.

In testimony whereof we affix our signatures in presence of two witnesses.

WILLIAM C. WARREN.
ARTHUR SMITHSON.
